UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

WINDOW-REGULATOR SPRING ASSEMBLY.

Application filed November 5, 1923. Serial No. 672,791.

To all whom it may concern:

Be it known that I, ERNEST E. HEINTZ, a citizen of the United States, residing at Detroit, in the county of Wayne and State of Michigan, have invented certain new and useful Improvements in Window-Regulator Spring Assemblies, of which the following is a specification.

This invention relates to window regulators and has for its object an improved counterbalancing spring retainer or cup. It is the object of the invention to provide a counterbalancing spring cup and a drum construction which will permit of a cheap and ready assembly and which will prevent the coil counterbalancing spring from drumming on the metal parts.

It is not broadly new to provide a spring cup for retaining the counterbalancing spring in a window regulator, such a cup construction is shown in the prior Allmand & Lawrence Patent No. 1,278,554. However, the present cup construction is quite different from the cup shown in the Allmand & Lawrence patent as that cup rotated with the drum or sprocket wheel while in the present construction the cup is stationary and becomes a permanent part of the regulator plate as will be more fully explained hereinafter.

In the drawings:

Fig. 1 is an elevational view of the upper portion of the regulator equipped with my improved cup construction and the improved drum assembly,

Fig. 2 is a horizontal section taken on the line 2—2 of Fig. 1.

Fig. 3 is a detailed section taken on the line 3—3 of Fig. 1.

Fig. 4 is a section taken on the line 4—4 of Fig. 2.

Fig. 5 is an inside elevation of the cup and the spring.

Fig. 6 is a section taken on the line 6—6 of Fig. 5.

Fig. 7 is a composite view showing the assembly of the spring cup drum and bearing stud.

a is the regulator plate. To this is attached the spacer bar b which supports the lower pulley wheel not shown. A cable c runs over the drum d and then over the driving spool e. The cable is anchored both to the driving spool and to the drum so that a positive movement is secured between

the cable and the drum and the sprocket and there is no occasion for any slippage of the cable on either the spool or drum. This is explained in my co-pending application Ser. No. 659,449, where this part of the construction is described and claimed. However, so far as the invention here claimed is concerned, the drum might be a sprocket wheel as well as a cable drum.

It is desirable in window regulators to have a counterbalancing spring which stores up energy on the descent of the window which energy helps to raise the window on the return movement of the window. This tends to equalize the driving effort in either direction. It is necessary, however, in the keen competition that has arisen in the regulator business to cheapen regulator construction as much as possible to meet both the market and to enlarge the field of usage of regulators so as to reach the lower priced cars. It is therefore expedient to so arrange production and the assembling operations that the cost of the counterbalancing element is reduced to a minimum; in fact in some of the cheaper cars the counterbalancing spring has been entirely eliminated in a regulator in order to bring the regulator price within the reach of the car.

I therefore employ a stamped metal cup g. This cup has a pair of lugs h stamped out of the bottom and a lug i turned up into the cup. This cup can obviously be made at one punching operation and one stamping operation. In the bottom of a cup is put a paper washer k to prevent rattling. The cups are either shipped to the spring manufacturer or the spring manufacturer makes them. These serve as a shipping container for the clock-like counterbalancing spring j. The lug i is the anchor for one end of the spring. This is turned up very close to the rim of the cup so that the spring may be fastened into the cup simply by bending over the end of the spring as at m. This very much lessens the cost of the spring as it is a rather difficult and expensive operation on these springs to form a complete loop which fits over a post as has often been the case in the past.

The spring retained in the cup is then shipped to the regulator manufacturer. The regulator manufacturer stamps the plate a with a boss n which is properly slotted so that the lugs h may be threaded through

the slots and then turned over and hammered down as at 1' (Fig. 2). This completes the assembly of the spring in the spring cup and onto the regulator plate.

- 5 The assembler then places the drum over the spring cup as shown in Figs. 7 and 2. He turns the drum around until the notch *s* in the hub of the drum registers with the inner end *o* of the counterbalancing spring. 10 When the notch has been slipped over the end of the counterbalancing spring then the spring is anchored to the rotating drum as well as to the stationary cup. The stud or rivet *p* is then inserted through the drum and the reduced end riveted over as shown in Fig. 2. The shoulder *q* between the reduced end and the main portion of the rivet serves to prevent any binding action on the rotatable member so that this stud forms a 15 free and easy bearing for the rotating member.

The drum is preferably a die casting but it may be a stamping. Another paper washer *s* is inserted in the bottom of the drum so 20 as to prevent the spring from contacting with the resonant metal at this side of the spring.

What I claim is:

1. In a window regulator having a rotatable member and a draft member movable thereover, the combination with said rotatable member, of a regulator plate, a separate spring cup anchored to the regulator plate and telescoping in the rotatable member, a counterbalancing spring anchored at one end in said cup and arranged to be contained therein before assembly of the cup in the plate and having the other end anchored to the rotating member. 30
2. In a window regulator having a rotatable member and a draft member movable thereover, the combination with the said rotatable member, a spring retaining cup telescoping into the rotatable member and provided with stamped out lugs, a regulator plate to which the cup is fastened by said lugs, and a coiled counterbalancing spring having one end anchored to the cup and the other end anchored to the rotatable member 40 and contained within the cup. 45
3. In a window regulator having a rotatable member and a draft member movable thereover, the combination with said rotatable member, of a spring retaining cup provided with an inwardly struck lug adjacent to the rim of the cup, a regulator plate to which the cup is anchored, the said cup telescoping into the rotatable member and a coiled counter-balancing spring having a 50 bent over end anchored to the cup by being dropped between the turned in lug and the rim of the cup and having its other end anchored to the rotatable member. 55
- 60
4. In a window regulator having a ro-

tatable member and a draft member movable 65 thereover, the combination with said rotatable member provided with an inwardly projecting hub having a notch therein, a spring cup, a regulator plate to which the cup is anchored by fastening devices, and a coiled counterbalancing spring having its outer end anchored to the cup and its inner end bent over and anchored to the rotatable member when the same is telescoped over the spring retaining cup. 70

5. In a window regulator having a rotatable member and a draft member movable thereover, the combination with said rotatable member provided with a notched hub, a spring cup having an outwardly projecting lug and an inwardly projecting lug adjacent to the rim, a regulator plate to which the cup may be fastened and a coiled counterbalancing spring which may be assembled in the cup before that member is fastened in place having its ends bent and one engaged between the turned in lug of the cup and the rim of the cup and the other end of the spring engaging in the notch in the rotatable member when the same is telescoped over the cup. 80

6. In a window regulator having a rotatable member and a draft member movable thereover, the combination with said rotatable member of a cup-like drum provided with an inwardly projecting notched hub, a spring retaining cup, a regulator plate to which the spring retaining cup is separately clamped, and a counterbalancing coiled spring having one end secured to the cup to anchor the same and the inner end engaged in the notch of the hub of the drum when the same is telescoped over the cup. 90

7. In a window regulator the combination of a regulator plate, a rotating member rotatably supported thereon and provided with a cup portion, a coiled counterbalancing spring engaging between the rotatable member and the regulator plate, and one or more paper washers located on the sides of the spring for deadening any vibration. 105

8. In a window regulator, the combination of a bossed regulator plate, a rotatable member provided with an inwardly projecting hub, and a shouldered rivet for riveting the hub of the rotatable member to the bossed portion so that the member will be rotatably supported, the reduced portion of the rivet being turned over on the inside of the boss to complete the assembly. 115

9. In a window regulator, a regulator plate, a cup member, a coil counterbalancing spring contained in said member, and a washer of fibrous material contained between the metal of the cup and the side of the counterbalancing spring. 120

In testimony whereof I affix my signature.
ERNEST E. HEINTZ.
